SEWING MACHINE

Rudolph Becker, North Plainfield, N. J., assignor
to The Singer Manufacturing Company, Elizabeth, N. J., a corporation of New Jersey

Application July 7, 1945, Serial No. 603,656

14 Claims. (Cl. 112—212)

1

This invention relates to sewing machines and more particularly to sewing machines having a so-called "clamp" feeding mechanism, i. e. work-feeding mechanism having synchronously acting feeding elements engaging the upper and lower faces of the work, and also automatic presser-foot lifting mechanism operated in timed relation with the feeding mechanism.

This invention has as a primary object to provide improved means for actuating the upper feeding mechanism and for automatically raising and lowering the presser-foot (or feet) in timed relation therewith.

Another object of the invention is to provide an improved top-feed and presser-foot lifting mechanism which is particularly adapted for heavy duty, multiple needle sewing machines.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a front elevation of a sewing machine embodying the present invention, with the face plate of the machine removed.

Fig. 2 is an enlarged vertical section of the bracket-arm head of the machine showing, in front view, the improved feed actuating and presser-foot lifting mechanism but omitting certain other mechanisms which form no part of the present invention.

Fig. 3 is a left end view of the parts shown in Fig. 2 together with a portion of the lower work-feeding mechanism, the loop-taker and a portion of its actuating mechanism.

Referring more specifically to the drawings, the invention is disclosed as embodied in a sewing machine having a frame comprising a pan-like bed or base 1, a standard 2 and an overhanging bracket-arm 3 terminating in a bracket-arm head 4. Journaled in bearings 5, lengthwise of the bracket-arm is a main or arm shaft 6 carrying, at its rear end, a combined belt and hand wheel 7 through which the shaft 6 is driven from any suitable source of power.

Mounted in the head 4, for endwise reciprocity, are two needle-bars 8, each having secured to its lower end, a needle carrying block 9. Secured in and extending through the blocks 9 are two horizontally disposed rods 10 upon which may

2

be adjustably secured a plurality of needle-carrying blocks, each similar to the blocks 9. Each of the blocks 9 is adapted to carry a needle N, only two of which are shown. Any suitable number of needle-carrying blocks may be mounted upon the rods 10 and by adjusting them along the rods and securing them thereto, any desired spacing of the needles and consequently any desired spacing of the seams formed thereby may be obtained.

Cooperating with each of the needles in the formation of stitches, is a chain stitch looper L, also of which only two are shown. These loopers may be of the thread-carrying variety or the non-thread-carrying variety dependent upon whether a two thread or single thread chain stitch seam is desired. The loopers L are secured in an oscillatory looper-carrier 12 in proper position to cooperate with its complementary needle. The 15 looper-carrier, and the loopers carried thereby, are given oscillatory and orbital movements from a rotary feed and looper actuating shaft 13, journaled in bearings 14 in the base, through mechanism designated generally as x. Inasmuch as the looper actuating mechanism forms no part of the present invention, detailed illustration and description thereof is deemed unnecessary.

The shaft 13 is rotated from the main shaft 6 through the medium of a one-to-one pulley and 20 clip-belt drive, located in a vertically disposed cavity 2a in the standard, and comprising a slotted pulley 6a on the shaft 6, a similar pulley 13a on the shaft 13 and a clip-belt 6b connecting these pulleys.

25 The needle-bars 8, and the needles carried thereby, are given endwise reciprocations from the arm shaft 6 through mechanism designated generally as y, and in timed relation with the movements of the loopers.

30 Secured upon the upper side of the bed 1 are suitable cover plates 1a and a work-supporting throat-plate 1b having therein slots 15 through which operates the feed-dog 16 forming a part of a lower four-motioned work-feeding mechanism f, hereinafter to be referred to. During the time that the feed-dog is below the upper face of the throat-plate, the work is held on the work-plate by two presser-feet 17 each pivotally mounted upon a shank 17a, secured to a collar 18a carried by the lower end of a spring-depressed presser-bar 18 mounted in the head 4.

35 The lower feeding mechanism may be of any suitable or preferred construction, such, for example, as that disclosed in my United States

patent application Serial No. 595,099, filed May 22, 1945.

Cooperating with the feed-dog 16 of the lower feeding mechanism in the feeding of the work, is an upper feeding and presser-foot lifting mechanism. This mechanism comprises two oscillatory and vertically movable upper feeding feet 19, each fulcrumed by a stud 20 in the tubular forward end portion 21 of an arm or radius bar 22 fulcrumed on a fixed stud 23 threaded into a boss 24 on the lower end of the bracket-arm head. Each feeding foot 19 is provided with a plurality of spaced and arcuate serrated portions 19a which operate through slots 17b in the sole portion 17c of the presser-feet 17.

Oscillatory movements are transmitted to the feeding feet 19, in timed relation with the feed and return movements of the lower feed-dog 16, from an eccentric 25 on the main shaft 6. This eccentric is surrounded by a strap 26 having a rearward extension 27 provided with a vertical bore or sleeve 28 in which is slidely fitted the cylindrical upper arm 29a of lever 29 formed integral with a stud 30 journaled in the bracket-arm head. The lower arm 29b of the lever 29 is in the form of a segment and has an arcuate slot 31 formed therein. Adjustably mounted in the slot 31 is a block 32 to which is pivotally connected one end of a link 33 the other end of which is pivotally connected to a rock-arm 34 fixed upon a horizontally disposed feed-drive rock-shaft 35 journaled horizontally in the bracket-arm head. Secured upon the outer ends of the shaft 35, exteriorly of the bracket-arm head, are two depending rock-arms 36, each pivotally connected to one end of a link 37, the other end of which is pivoted at 38 to the upper end of one of the feeding feet 19.

From the foregoing it will be understood that through the mechanism above described, rotation of the eccentric 25 effects oscillatory or feed and return movements in the feeding feet 19 about the axes of the studs 20. The amplitude of oscillation of these feet may be varied by adjusting the block 32 in the slot 31 nearer to or farther from the axis of oscillation of the lever 29.

The feeding feet 19 are also given rising and falling movements in timed relation with their feed and return movements. These rising and falling movements are derived from an eccentric 39, on the main shaft 6. Surrounding the eccentric 39 is the strap end 40a of a pitman 46, the other end of which is pivotally connected, at 40b, with the outer end of a rock-arm 41, fixed upon a feed-lift rock-shaft 42 journaled horizontally in the bracket-arm head 4. Secured upon the outer ends of the shaft 42 are two rock-arms 43, each pivotally connected to the upper end of a link 44, the lower end of which is pivoted to one end of a lever 45, pivoted, at 46, to one of the collars 18a on one of the presser-bars. Intermediate its ends each lever 45 is pivotally connected, at 45a, to the upper end of a link 47 the lower end of which is pivoted to one of the radius bars 22, hereinbefore mentioned. Thus rotation of the eccentric 39 swings the anchor links 22 vertically about their pivots 23 thereby successively lifting and depressing the feeding feet 19 fulcrumed upon the forward ends thereof.

During one-half rotation of the shaft 6 and the eccentric 39 carried thereby, downward movement of the pitman 46, the arms 43 and links 44 turn the levers 45 about their pivots 46, whereupon the levers function as levers of the second order and depress the bars 22 and the feeding feet 19 piv-

oted thereto. When the feeding feet have engaged the work and have compressed it upon the throat-plate, and the feet therefore cannot be further depressed, further downward movement of the pitman 46, arms 43 and links 44 causes the levers 45 to turn about the pivots 45a and thus function as levers of the first order to raise the pivots 46, the presser-bars 18, collars 18a, shanks 17a and the presser-feet 17 carried by said shanks, thus taking the pressure of the presser-feet off the work during the time that the feeding feet 19 are oscillated rearwardly and the feed-dog 16 is reciprocated to feed the work.

During the other half rotation of the shaft 6 and eccentric 39, the pitman 46, arms 43 and links 44 are moved upwardly thus first causing the presser-feet to be lowered upon the work after which further movement of the parts causes the levers 45, links 47 and radius bars 22 to raise the feeding feet 19 preparatory to their forward oscillation by the elements 25 to 37.

From the foregoing it will be perceived that this invention has provided an improved top-feed and presser-foot lifting mechanism particularly adapted for heavy duty, multiple needle sewing machines and which may be used either separately as a top-feed mechanism or in conjunction with a suitable lower four-motioned feeding mechanism such, for example, as that disclosed in my above mentioned application, as an upper and under or "clamp" feeding mechanism.

It will also be apparent that, although the top-feed is disclosed in a heavy duty, wide gauge, multiple needle sewing machine and as including two feeding feet 19 cooperating with two presser-feet 17, the invention is equally adaptable to lighter duty sewing machines having but a single upper feeding foot and a single cooperating presser-foot.

Having thus set forth the nature of the invention, what I claim herein is:

1. In a sewing machine having a frame including a bracket-arm, a bracket-arm head and a work-supporting plate; a rotary shaft journaled in said frame; an upper work-feeding mechanism located entirely above said work-supporting plate and comprising an arm fulcrumed on said head; a vertically disposed feeding-foot pivoted intermediate its ends to the free end of said arm and having a serrated work-engaging portion; feed-drive and feed-lift elements carried by said shaft; and operative connections between said elements and said feeding-foot including an endwise movable link connected with said feeding-foot at one side of the pivot thereof for giving to said foot feed and return movements and rising and falling movements.

2. In a sewing machine, a combination, a frame including a bracket-arm head and a work-supporting plate; a lower four-motioned work-feeding mechanism including a feed-dog located beneath said work-supporting plate; a rotary shaft journaled in said frame; an upper work-feeding mechanism located entirely above said work-supporting plate and comprising a radius bar fulcrumed on said head; a feeding-foot pivoted to the free end of said radius bar; feed-drive and feed-lift eccentrics carried by said shaft; and operative connections between said eccentrics and said feeding-foot for giving to said foot feed and return movements and rising and falling movements in timed relation with the movements of the feed-dog of the lower work-feeding mechanism.

3. In a sewing machine, in combination, a

frame including a bracket-arm head and a work-supporting plate; a lower four-motioned work-feeding mechanism including a feed-dog located beneath said work-supporting plate; a presser-foot opposed to said work-supporting plate and provided with a slot; a rotary shaft journaled in said frame; an upper work-feeding mechanism located entirely above said work-supporting plate and comprising an arm fulcrumed on said head; a feeding-foot pivoted to the free end of said arm and having a serrated portion extending through the slot in said presser-foot; feed-drive and feed-lift eccentrics carried by said shaft; and operative connections between said eccentrics and said feeding-foot for giving to said foot feed and return movements and rising and falling movements in timed relation with the movements of the feed-dog of the lower work-feeding mechanism.

4. In a sewing machine having a frame including a bracket-arm, a bracket-arm head and a work-supporting plate; a rotary shaft journaled in said frame; an upper work-feeding mechanism located entirely above said work-supporting plate and comprising a radius bar fulcrumed on said head; a feeding-foot pivoted to the free end of said radius bar; feed-drive and feed-lift eccentrics carried by said shaft; an operative connection between said feed-lift eccentric and said feeding-foot for giving to said foot rising and falling movements; an operative connection between said feed-drive eccentric and said feeding-foot for giving to said foot feed and return movements in timed relation with its rising and falling movements; and means embodied in the last named connection for varying the stroke of said feeding foot.

5. In a sewing machine, in combination, a frame including a bracket-arm head and a work-supporting plate; a lower work-feeding mechanism including a four-motioned feed-dog located beneath said work-supporting plate; a rotary shaft journaled in said frame; two spring-depressed presser-bars mounted in said head; a presser-foot carried by each of said presser-bars and each having a sole portion provided with a slot; an upper work-feeding mechanism located entirely above said work-supporting plate and comprising two radius bars fulcrumed on said head; a feeding-foot pivoted to the free end of each of said radius bars, each of said feeding feet having a serrated portion extending through a slot in one of said presser-feet; feed-drive and feed-lift eccentrics carried by said shaft; operative connections between said feed-drive eccentric and said feeding-feet for giving to said feet feed and return movements in timed relation with the movements of the feed-dog of the lower work-feeding mechanism; and means actuated by said feed-lift eccentric and connected with said radius bars for alternately raising and lowering said feeding-feet and presser-feet.

6. In a sewing machine, in combination, a frame including a bracket-arm, a bracket-arm head and a work-supporting plate; a spring-depressed presser-bar mounted in said head; a presser-foot carried by said presser-bar; a rotary shaft journaled in said bracket-arm; an upper work-feeding mechanism located entirely above said work-supporting plate and comprising a radius bar fulcrumed on said head; a feeding-foot pivoted to the free end of said radius bar; feed-drive and feed-lift eccentrics carried by said shaft within said head; means actuated by said feed-drive eccentric and connected with the feeding-foot to

give to said feeding-foot feed and return movements; and means actuated by said feed-lift eccentric and connected with said radius bar and with said presser-bar for alternately raising and lowering said feeding-foot and said presser-foot.

7. In a sewing machine having a frame including a bracket-arm, a bracket-arm head carried thereby and a work-supporting plate; a plurality of spring-depressed presser-bars mounted in said head; a presser-foot supported by the lower end of each of said presser-bars, each of said presser-feet having a sole portion provided with a plurality of parallel slots; a work-feeding mechanism located wholly above said work-supporting plate and comprising two arms fulcrumed on said bracket-arm head adjacent the opposite sides thereof; a feeding-foot pivoted to each of said arms and having serrated portions extending through the slots in said presser-feet; means to oscillate said feeding-feet about their pivots to effect feed and return movements thereof; and means to give to said arms, and thereby to the feeding-feet, rising and falling movements in timed relation with their feed and return movements.

8. In a sewing machine having a frame including a bracket-arm, a bracket-arm head carried thereby and a work-supporting plate; a plurality of spring-depressed presser-bars mounted in said head; a shank secured to the lower end of each of said presser-bars; a presser-foot supported by each of said shanks, each of said presser-feet having a sole portion provided with a plurality of parallel slots; a work-feeding mechanism located wholly above said work-supporting plate and comprising two arms fulcrumed on said bracket-arm head adjacent the opposite sides thereof; a feeding-foot pivoted to each of said arms and having serrated portions extending through the slots in said presser-feet; means to oscillate said feeding-feet about their pivots to effect feed and return movements thereof, and means connected with said arms and with said presser-bars for alternately raising and lowering said feeding-feet and presser-feet.

9. An upper work-feeding mechanism for a sewing machine having a frame including a bracket-arm, a bracket-arm head and a work-supporting plate; comprising a rotary shaft journaled in said bracket-arm; feed-drive and feed-lift eccentrics on said shaft; horizontally disposed feed-drive and feed-lift rock-shafts journaled in said bracket-arm head; operative connections between said feed-drive and feed-lift eccentrics and said feed-drive and feed-lift rock-shafts, respectively; an arm fulcrumed on said head; a feeding-foot pivoted to said arm; means actuated by said feed-drive rock-shaft for moving said feeding-foot about its pivot to give to said foot feed and return movements; and means actuated by said feed-lift rock-shaft to raise and lower said arm to give to said feeding-foot vertical movements in timed relation with its feed and return movements.

10. An upper work-feeding mechanism for a sewing machine having a frame including a bracket-arm, a bracket-arm head and a work-supporting plate; comprising a rotary shaft journaled in said bracket-arm; feed-drive and feed-lift eccentrics secured to said shaft within said head; horizontally disposed feed-drive and feed-lift rock-shafts journaled in said bracket-arm head; operative connections between said feed-drive and feed-lift eccentrics and said feed-drive and feed-lift rock-shafts, respectively; a pair of

radius bars fulcrumed on said head; a feeding-foot pivoted intermediate its ends to the free end of each of said radius bars; means actuated by said feed-drive rock-shaft and engaging the upper ends of said feeding-feet for oscillating said feeding-feet about their pivots to give to said feet feed and return movements; and means actuated by said feed-lift rock-shaft to raise and lower said arms to give to said feeding-feet vertical movements in timed relation with their feed and return movements.

11. An upper work-feeding mechanism for a sewing machine having a frame including a bracket-arm, a bracket-arm head and a work-supporting plate; comprising a rotary shaft journaled in said bracket-arm; feed-drive and feed-lift eccentrics on said shaft; horizontally disposed feed-drive and feed-lift rock-shafts journaled in said bracket-arm head; means to actuate said feed-lift rock-shaft from said feed-lift eccentric; a vertically disposed two-armed member fulcrumed within said bracket-arm head; a pin-and-sleeve driving connection between the upper arm of said member and said feed-drive eccentric; an operative connection between the lower arm of said member and said feed-drive rock-shaft whereby rotation of said feed-drive eccentric effects oscillation of said two-armed member and said feed-drive rock-shaft; an arm fulcrumed on said head; a feeding-foot pivoted to said arm; means actuated by said feed-drive rock-shaft for moving said feeding-foot about its pivot to give to said foot feed and return movements; and means actuated by said feed-lift rock-shaft to raise and lower said arm to give to said feeding-foot vertical movements in timed relation with its feed and return movements.

12. A work-feeding mechanism for a sewing machine as set forth in claim 11 in which the lower arm of the vertically disposed two-armed member is formed as a segment; in which a rock-arm is secured to and projects from the feed-drive rock-shaft; and in which oscillatory motion is transmitted to said feed-drive rock-shaft from said two-armed member by a link which is pivoted at one end to the rock-arm and has its other end adjustably secured to said segment.

13. An upper work-feeding mechanism for a sewing machine having a frame including a bracket-arm, a bracket-arm head and a work-supporting plate; comprising a rotary shaft jour-

naled in said bracket-arm; feed-drive and feed-lift eccentrics on said shaft; horizontally disposed feed-drive and feed-lift rock-shafts journaled in said bracket-arm head; an operative connection between said feed-drive eccentric and said feed-drive rock-shaft; a first rock-arm secured to and projecting from said feed-lift rock-shaft; a pitman having one end surrounding said feed-lift eccentric and its other end connected to said first rock-arm; a second rock-arm secured to said feed-lift rock-shaft; a radius bar fulcrumed on said head; a feeding-foot pivoted to said arm; means actuated by said feed-drive rock-shaft for moving said feeding-foot about its pivot to give to said foot feed and return movements; and means actuated by said second rock-arm to raise and lower said radius bar to give to said feeding-foot vertical movements in timed relation with its feed and return movements.

14. An upper work-feeding mechanism for a sewing machine having a frame including a bracket-arm, a bracket-arm head carried thereby, and a work-supporting plate; comprising a rotary shaft journaled in said bracket-arm; a feed-drive eccentric and a feed-lift eccentric on said shaft; horizontally disposed feed-drive and feed-lift rock-shafts journaled in said bracket-arm head; operative connections between said feed-drive and feed-lift eccentrics and said feed-drive and feed-lift rock-shafts, respectively; two arms fulcrumed on said bracket-arm head adjacent the opposite sides thereof, said arms being arranged substantially horizontal and parallel to each other; a feeding-foot pivoted to each of said arms; means actuated by said feed-drive rock-shaft for moving each of the feeding-feet about its pivot to give said feet feed and return movements; and means actuated by said feed-lift rock-shaft to raise and lower said arms to give to said feeding-feet vertical movements in timed relation with their feed and return movements.
